US0D1097657S

(12) **United States Design Patent** (10) **Patent No.:** **US D1,097,657 S**
(45) **Date of Patent:** **** Oct. 14, 2025**

(54) **RETAIL FIXTURE**

- (71) Applicant: **Apple Inc.**, Cupertino, CA (US)
- (72) Inventors: **Alice Marlin Brugger**, Sonoma, CA (US); **Manuel Dejesus**, San Francisco, CA (US); **Joshua Robert Edwards**, Santa Cruz, CA (US); **Jean-Marc Gady**, Menlo Park, CA (US); **Wesley Bryan Hamm**, San Francisco, CA (US); **Russell John Kaaihue Heirakuji**, San Jose, CA (US); **Allison Inouye**, San Francisco, CA (US); **Moritz Wilsberg**, Rheinbreitbach (DE)
- (73) Assignee: **Apple Inc.**, Cupertino, CA (US)
- (**) Term: **15 Years**
- (21) Appl. No.: **29/959,440**
- (22) Filed: **Aug. 26, 2024**

Related U.S. Application Data

- (63) Continuation of application No. 29/859,080, filed on Nov. 7, 2022, now Pat. No. Des. 1,039,882, which is a continuation of application No. 29/807,409, filed on Sep. 10, 2021, now Pat. No. Des. 968,858, which is a continuation of application No. 29/759,216, filed on Nov. 20, 2020, now Pat. No. Des. 930,405, which is a continuation of application No. 29/738,126, filed on Jun. 15, 2020, now Pat. No. Des. 904,083, which is a continuation of application No. 29/655,973, filed on Jul. 9, 2018, now Pat. No. Des. 887,185.

CLAIM

The ornamental design for a retail fixture as shown and described.

DESCRIPTION

FIG. 1 is a top front perspective view of a retail fixture showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the retail fixture that form no part of the claimed design.

1 Claim, 5 Drawing Sheets
